United States Patent Office.

IRA FLANDERS, OF PAW PAW, MICHIGAN.

Letters Patent No. 95,217, dated September 28, 1869.

IMPROVEMENT IN STUMP-EXTRACTOR.

The Schedule referred to in these Letters Patent and making part of the same.

To all whom it may concern:

Be it known that I, IRA FLANDERS, of Paw Paw, in the county of Van Buren, and State of Michigan, have invented certain new and useful Improvements in "Stump-Extractors;" and I do hereby declare that the following is a true and correct description of the same, reference being had to the accompanying drawings, and the letters of reference marked thereon, which constitute a part of this specification.

The object of my invention is to provide a machine for extracting stumps, in such a manner as that new power and purchase may be obtained after the stump is started from its bed, without losing any of the advantage gained, and without removing from the stump the lifting-chain.

To enable others skilled in the art to construct and operate my invention, I will proceed to describe it more fully.

Figure 1 is a perspective view of my machine, showing all the parts in detail.

Figure 2 is a side view, with one end of frame removed.

I construct a strong frame, with sills A A, posts B B, braces c c c, secured to sills by means of chains a a a a, and cross-beam D.

My posts, B B, stand perpendicularly, while the braces incline in two directions, thus giving great strength and security.

Suspended to the cross-beam D is a sweep, E, having for its fulcrum a link and staple, the link passing up through a mortise in the cross-beam, and being secured by key b.

In one end of the sweep are two sheaves, d d, over which the rope F passes to and from the block H, in connection with which it forms a "tackle and fall."

In the other end the sweep is cut out, as shown in fig. 1, to enable the lifting-chain J to be moved toward or from the fulcrum, as desired, so that the lifting-arm of the sweep may be made long or short, at will.

Near the end of the lifting-arm of the sweep, on both sides, is an iron plate, f f, bolted on by bolts extending through the sweep.

Passing through these plates is a shaft, s, with two cog-wheels, not shown in drawings, which work the two cogged rails g g of the sliding fulcrum o.

The two rails g g are independent, and are held in place by a roller, x, which is turned down so as to leave shoulders for each one to run between.

On the inner end of these two rails rests a large iron pin, which supports a strong link, through which passes the lifting-chain J, as shown in fig. 2.

By means of the crank K, the rails g g are moved forward or back.

To each end of the cross-beam is suspended a pulley, h h.

Below those, and secured to one of the braces and the posts, are crank-shafts, L L, each having on the end a ratchet-wheel, k, with pawl, as shown in fig. 1.

Extending from the crank-shafts, and running over the pulleys h h, are ropes, j j, with hook in the ends.

The manner of operating my machine is as follows:

Placing it above a stump, I lower the lifting-arm and place the lifting-chain about the stump with a half-hitch. I then lower the block H, and hook it to the lifting-chain. I run the movable fulcrum o back, to make a short arm, so as to get great power. Then, hooking my team to the end of rope F, at hook y, I am ready to operate upon the stump.

By locking my block H to the lifting-chain, I secure all the power of the machine for the lifting of the stump.

When I have exhausted the scope of the sweep, I attach the side ropes j j, by hooking them into the lifting-chain, and then wind them both up taut, so that I hold the stump at the point to which it has been raised.

I then slacken the rope F, so as to lower the lifting-arm of the sweep, when I run the movable fulcrum out, and thus make a long arm, and again apply my power and remove my stump, without disturbing my lifting-chain or readjusting the same.

Having thus fully described my invention,

What I claim as new, and desire to secure by Letters Patent, is—

1. The sliding fulcrum o, with cogged rails g g, crank k, plates f f, roller x, and cogged wheels, on shaft s, as combined and operated, for the use and purpose as specified.

2. The crank-shafts L L, ratchet-wheels and pawls k k, pulleys h h, and ropes j j, as combined and operated, for the use and purpose herein specified and set forth.

3. A stump-extractor, as constructed, combined, and operated, for the use and purpose as specified and herein set forth.

In testimony whereof, I have signed my name to this specification, in the presence of two subscribing witnesses.

IRA FLANDERS.
